(57) **CLAIM**

The ornamental design for the chair, as shown and described.

DESCRIPTION

FIG. 1 is a front perspective view of the chair showing our new design.

FIG. 2 is a front perspective of the chair showing our design according to a second embodiment.

FIG. 3 is a front view of the chair showing our design according to a second embodiment.

FIG. 4 is a rear view of the chair showing our design according to a second embodiment.

FIG. 5 is a left side view of the chair showing our design according to a second embodiment.

FIG. 6 is a right side view of the chair showing our design according to a second embodiment.

FIG. 7 is a top view of the chair showing our design according to a second embodiment.

FIG. 8 is bottom view of the chair showing our new design according to a second embodiment.

FIG. 9 is a front perspective view of the chair showing our design according to a third embodiment.

FIG. 10 is front perspective view of the chair showing our design according to a fourth embodiment.

FIG. 11 is a front view of the chair showing our design according to a fourth embodiment.

FIG. 12 is a rear view of the chair showing our design according to a fourth embodiment.

FIG. 13 is a left side view of the chair showing our design according to a fourth embodiment.

FIG. 14 is a right side view of the chair showing our design according to a fourth embodiment.

FIG. 15 is a top view of the chair showing our design according to a fourth embodiment; and,

FIG. 16 is bottom view of the chair showing our new design according to a fourth embodiment.

The dash-dot-dash broken lines in the drawings represent symbolic breaks in length and form no part of the claimed design.

1 Claim, 14 Drawing Sheets
